PROCESS FOR MAKING YARN PACKAGES

Ki Williams, Waynesboro, Va., assignor, by mesne assignments, to E. I. du Pont de Nemours & Company, Wilmington, Del., a corporation of Delaware

Application November 19, 1935, Serial No. 50,562

2 Claims. (Cl. 117—26)

This invention relates to the production of a shipping package of twisted thread, and more particularly it relates to a method for the production of an improved light weight shipping package of twisted thread by a single winding and uptwisting operation, which package will be suitable for direct use in the production of fabrics. 5

The present invention is particularly applicable to the production of twisted threads of organic 10 derivatives of cellulose, for example, cellulose esters such as cellulose acetate, cellulose propionate, cellulose acetopropionate, cellulose stearate, and cellulose ethers such as ethyl cellulose and benzyl cellulose, in view of the necessary 15 step of heating such twisted yarn in a moist atmosphere to set the twist imparted thereto. The invention will be described in detail with particular reference to cellulose acetate, it being understood that the invention is not to be limited 20 thereto but applies broadly to organic derivatives of cellulose.

Prior to the present invention, a commonly used 25 method of producing shipping packages of twisted cellulose acetate yarn suitable for direct use in the production of fabrics involved the following essential operation:

Cellulose acetate yarn, after spinning, drying and dressing with a finishing composition, was collected on supply bobbins. These supply bobbins 30 were placed on a spindle of an uptwisting machine and uptwisted over the end of the supply bobbin as the latter revolved in a vertical position at a high rate of speed, and onto a rotating wooden receiving spool which rotates at a constant peripheral speed in a horizontal position. 35 The number of twists per inch imparted to the cellulose acetate thread was determined by the ratio of the number of revolutions per minute of the supply bobbin to the wind-up speed of the 40 thread in inches per minute on the receiving bobbin. The wooden receiving bobbins were then placed in a heated, moist atmosphere for a certain period of time for the purpose of setting the 45 twist imparted to the thread. The receiving bobbins were subsequently placed on a winding or coning machine and the twisted threads were 50 unwound from the receiving bobbins and precision wound onto light pasteboard cones or light weight metallic spools. These light weight cones or spools are suitable for shipping purposes, and due 55 to their being precision wound will permit ready removal of the thread during subsequent textile producing operations.

By the term "precision wound" as used through- 55 out the specification and claims is meant winding

of thread into a package with such smoothness, uniformity and orderliness that the package will remain firm during shipment and the thread will unwind therefrom without tangling, clinging or sloughing. 5

This procedure necessarily involves two winding operations, namely the winding from the supply bobbin to a receiving spool, and from the receiving spool to the shipping core. This double winding procedure is undesirable due to high handling and operating expense and the requirement of a large amount of floor space and additional equipment and labor. Furthermore, the double winding results in an unavoidable increase in the 10 number of knots per package of yarn and in an 15 inevitable degradation and lowering of the quality of the yarn because of the additional handling 20 operation.

The shipping of the yarn on the wooden receiving spools would be uneconomical due to the excessive weight of said spools. Thread wound on wooden receiving spools is unsatisfactory for use in the manufacture of textiles due to the susceptibility to breakage of the thread during the 25 unwinding thereof. On the other hand, the use 30 of wooden receiving bobbins has been considered essential heretofore in the production of twisted cellulose acetate thread by reason of their resistance to the heated, moist atmosphere necessary in the setting of the twist of the thread. 35

It is therefore an object of the present invention to produce, by a single winding and uptwisting operation, shipping packages of twisted cellulose acetate thread in which the twist has been set and which is suitable for direct use in 40 fabrics. 45

It is a further object of this invention to provide a light weight, receiving bobbin suitable for use as a shipping core and which will withstand the hot, moist atmosphere to which bobbins or 40 spools of twisted cellulose acetate must be subjected to set the twist in the thread.

It is another object of this invention to up-twist and wind a cellulose acetate thread directly into a shipping package which may be subjected 45 to a hot, moist atmosphere for setting of the twist in the thread, and which is precision wound with squared edges and is substantially free of over-thrown ends.

Other objects of the invention will appear here- 50 inafter.

The objects of the invention are accomplished in general by up-twisting a cellulose acetate thread from a supply bobbin, collecting said 55 twisted thread by precision winding the same on

- a headless, cylindrical, light weight core which is impregnated or coated with a material to render it smooth and insensitive to the hot, moist atmosphere necessary for setting the twist in said thread. The precision winding is carried out in such a manner that the traverse of the thread longitudinally of the package is not substantially less than 1.36 inches for each revolution of the thread about the package.
- 10 The twisted thread must be wound on a light weight, headless, cylindrical core which is impregnated or coated with a material to render it smooth and insensitive to the heated, moist atmosphere which is necessary for the setting of the twist in the thread for several reasons. The core must be light weight and headless so that the resulting package may be economically shipped to the desired points of destination without adding unnecessarily to the weight of the thread.
- 15 The core must be cylindrical so that the package may be wound with precision by a surface drive mechanism and will have uniform density and a minimum of, or no overthrown loops projecting from the ends of the package.
- 20 The core must be cylindrical so that the package may be wound with precision by a surface drive mechanism and will have uniform density and a minimum of, or no overthrown loops projecting from the ends of the package.
- 25 If the core were conical, the resulting package would have irregular hardness or density, poorly formed ends, and many overthrown loops, with the result that the thread would be damaged and degraded. This is due to the fact that the point 30 of contact of the cone with the surface drive wheel will shift from one end to the other and consequently the rotational speed of the cone will constantly vary. When the point of contact between the surface drive wheel and the core is at 35 the large end of the cone, the latter will rotate more slowly than when the point of contact is at the small end of the cone.
- The core must be impregnated or coated with a protective substance which will render the core 40 insensitive to hot, moist atmosphere used in setting the twist in the thread by reason of the fact that this operation must necessarily be carried out on the shipping core, to prevent double winding. Furthermore, this coating must be smooth 45 to prevent abrasion or degradation of the yarn.
- Such light weight cylindrical cores can be constructed of a great many known materials such as fiber, paper, pasteboard, laminated cloth, and the like. The core is coated or impregnated with a 50 substance which upon drying or other treatment will render the same insensitive to the atmospheric conditions present in the setting of the twist. The core may, for example, be given the well known zinc chloride treatment. Alternatively, the core may be impregnated with a phenol-aldehyde resin of the "bakelite" type or other synthetic or natural resin with or without modifying 55 constituents.
- The thread is precision-wound on the core so 60 that the packages will be firm and evenly wound to withstand shipment, and will unwind with facility during the subsequent textile operations. The precision-winding is carried out in such a manner that the traverse of the thread longitudinally of the package is not substantially less than 1.36 inches for each revolution of the thread about the package whereby to prevent sloughing of the thread from the ends of the package and to substantially eliminate over-thrown ends.
- 65 It is only by combining these various steps of procedure that a shipping package of the type set forth can be produced with a single winding operation. Although one or more of the detailed steps set forth above may have utility in obtaining a somewhat improved package by the double

winding procedure known heretofore, nevertheless, it is only by the functional cooperation of the several steps that a suitable shipping package which is acceptable in the trade, can be produced with a single winding operation.

5

In adapting conventional uptwisting equipment for use in carrying out the present invention, the conventional receiving take-up spool may be replaced by a wooden spindle having an external diameter of such a size as to form a snug fit with the internal surface of the cylindrical shipping core.

10

The construction of the cylindrical shipping core and the wooden spindle will be more clearly apparent by reference to the following detailed description taken in connection with the accompanying illustration in which:

15

Figure 1 is a perspective view of a shipping cone constructed in accordance with the invention;

20

Figure 2 is a perspective view of a wooden spindle constructed in accordance with the present invention.

25

Figure 3 is a diagrammatic view showing the spinning of cellulose acetate thread and collecting the thread on a supply bobbin;

25

Figure 4 is a diagrammatic view showing the twisting and precision-winding of cellulose acetate thread from the supply bobbin onto a cylindrical shipping core; and

30

Figure 5 shows diagrammatically the removable shipping core mounted on a spindle assembly.

35

Referring to the drawings, reference numeral 11 designates generally the cylindrical shipping core. This core is preferably provided at one end 40 thereof with a groove 12 around which the thread may be wrapped a plurality of turns prior to its being precision-wound on the shipping core. The thread positioned in this groove will function as a tailing which is highly advantageous for continuous operation of textile machinery. Thus, the transfer tail on the first core is tied to the starting thread of the second core before the first shipping core has been unwound and is to be replaced by the second package. The cylindrical 45 core 11, as stated above, is coated or impregnated with a material which will render it impervious to hot, moist atmospheric conditions.

40

Reference character 13 generally designates the wooden spindle which is preferably provided 50 with groove 14 and springs 16. The springs 16 are adapted to slide within the groove 14 and are anchored in the spindle by means of the leg 17. The spindle is furthermore provided with a shaft 15 which is adapted to be mounted in spaced 55 grooves of an up-twisting machine in which they are adapted to be rotated by means of surface drive mechanism in the same manner as is well known with receiving take-up bobbins. The springs 16 are adapted to contact with the internal surface of the cylindrical core 11 and thereby hold the cylindrical core 11 firmly on the wooden spindle 13 to prevent relative rotation therebetween.

45

The shipping core and wooden spindle assembly are preferably dynamically balanced so that the take-up core upon which the thread is collected will rotate smoothly to permit precision winding of the thread thereon.

50

Figure 3 illustrates diagrammatically the spinning and collecting of cellulose acetate thread, a cellulose acetate solution being introduced through supply pipe 18 and spinning nozzle 19 into spinning cell 20, the thread passing around a guide 21, through an aperture in the spinning

75

70

cell and being collected as a supply package 22 on supply bobbin 23 mounted on spindle 24. Referring to Figure 4, supply package 22 and supply bobbin 23 are mounted on a spindle 24 of an up-twister, spindle 24 being driven by means of pulley 25 driven by a belt 26. The thread passes through guide 27, being collected onto the removable cylindrical shipping core 11 mounted on spindle 13 rotating in bearings 28, the precision-winding of the twisted thread being effected by means of a traverse guide 29 mounted on traverse bar 30. Shipping core 11 and spindle assembly 13 are rotated by surface contact with a drive roll 31 which is suitably driven from an external source of power.

Figure 5 is an end view showing spindle assembly 13 and the removable shipping core 11 with the twisted, precision-wound yarn thereon, the shipping core being firmly held on the spindle 20 to prevent relative rotation therebetween.

The outstanding advantage of the present invention is the provision of a light weight shipping package of twisted cellulose acetate yarn with a single winding operation. It is evident 25 that this elimination of the usual coning or spooling step after the twisting operation results in a decided economy and considerable improvement in the quality of the yarn. Furthermore, the invention is applicable to standard up-twisting equipment without the necessity of providing for a costly and time-consuming modification in the equipment.

Obviously, many modifications and changes 30 may be made in the above description without departing from the nature and spirit thereof, and it is therefore to be understood that the invention

is not to be limited thereto except as set forth in the appended claims.

I claim:

1. The method of producing a light-weight shipping package of twisted cellulose derivative 5 thread, comprising forming a cellulose derivative thread from a cellulose derivative spinning solution and collecting said thread on a supply bobbin, uptwisting and simultaneously precision-winding said thread from said supply bobbin 10 onto a light-weight cylindrical core which is removable from its spindle, said precision winding operation being carried out with a thread traverse longitudinally of the package not substantially less than 1.36 inches for each revolution of 15 the thread about the package.

2. The method of producing a light-weight shipping package of twisted cellulose derivative 20 thread, comprising forming a cellulose derivative thread from a cellulose derivative spinning solution and collecting said thread on a supply bobbin, uptwisting and simultaneously precision-winding said thread from such supply bobbin onto a smooth light-weight, headless, cylindrical 25 core which is removable from its spindle and which is insensitive to the hot, moist atmosphere necessary for setting the twist in the thread, said precision winding operation being carried out with a thread traverse longitudinally of the package not substantially less than 1.36 inches for 30 each revolution of the thread about the package, and subjecting said twisted thread to atmospheric conditions which are sufficiently hot and moist to set the twist in said thread.

35
